No. 760,891.

PATENTED MAY 24, 1904.

G. H. MARR.

DIAPHRAGM SCREEN OPERATING MECHANISM.

APPLICATION FILED JAN. 14, 1904.

NO MODEL.

UNITED STATES PATENT OFFICE.

GEORGE HENRY MARR, OF WATERVILLE, MAINE.

DIAPHRAGM-SCREEN-OPERATING MECHANISM.

SPECIFICATION forming part of Letters Patent No. 760,891, dated May 24, 1904.

Application filed January 14, 1904. Serial No. 189,043. (No model.)

To all whom it may concern:

Be it known that I, GEORGE HENRY MARR, a resident of Waterville, in the county of Kennebec and State of Maine, have invented certain new and useful Improvements in Diaphragm-Screen-Operating Mechanism; and I do hereby declare the following to be a full, clear, and exact description of the invention, such as will enable others skilled in the art to which it appertains to make and use the same.

My invention relates to improved diaphragm-screen-operating mechanism, the object of the invention being to operate the screen by fluid-pressure—such as air, gas, or liquid might in some instances be employed; and it consists in certain novel features of constructions and combinations and arrangements of parts, as will be more fully herein-after described, and pointed out in the claims.

In the accompanying drawings, Figure 1 is a view in vertical section illustrating my improvements. Fig. 2 is a view in section on the line $y z$ of Fig. 1. Fig. 3 is a view in section on the line $w w$ of Fig. 1, and Fig. 4 is a view in section on the line $x x$ of Fig. 1.

In the pulp and paper making industry all of the pulp used passes through screens which usually consist of brass plates three-eighths inch thick, with slots about one one-hundredth inch wide, the slots being about six inches long and spaced about three-eighths inch apart. A diaphragm working under the plates creates a vacuum on its downstroke and draws through the slots such particles of pulp as are fine enough, and the return motion of the diaphragm creates a pressure under the plates, lifting the coarse particles of pulp which have lodged over the slots, thus freeing them so that the vacuum-stroke of the diaphragm will take through the slots another lot of fine pulp.

In nearly all of the diaphragm-screens now in use the motion of the diaphragm is obtained by means of a cam secured to a revolving shaft. A shoe, of wood or other material, resting on the cam and secured to the end of a suitable connection with the diaphragm-plate imparts the necessary motion to the diaphragm. Each cam operates its diaphragm at the rate of about seven hundred strokes per minute, and the wear on the shoe

is so great that it requires frequent renewals, especially in some makes of screens. The jar of the cam loosens and breaks other parts of the screens and calls for constant repair on them, resulting in a large repair account and comparatively short life to the screens. The noise and jar produced by the cams is a source of great annoyance.

In order to overcome the above objections, my improvements were devised and will now be described in detail.

The method which I have devised is intended to displace the driving-pulley, cam-shaft, cam-shaft boxes, cams, cam-shoes, and cam-shoe holders of the screens as ordinarily constructed, and consists of a casting A, Fig. 1, of proper shape and design to contain the working parts of the device, secured to the screen-frame B B by the bolts a and dowel-pins a' and provided with a cap a'' , held in position by studs a^3 and nuts a^4 . Cap a'' holds in position a bronze bushing b' , which serves as a guide for the diaphragm-rod r' , which passes through it.

To one end of the diaphragm-rod is secured by set-screw c the holder C, into which is threaded the piston D, fitted with grooves d and d' . Radial holes d^2 communicate with the chamber d^3 , and radial holes d^4 communicate with the chamber d^5 . Holes d^6 allow the use of a spanner-wrench for screwing or unscrewing piston D from the holder C, and the hexagonal recess d^7 in piston D allows the use of a hexagonal wrench for the same purpose after removing the screwed plug I. Circumferential grooves d^8 on piston D serve to pack same and to hold lubricants.

A bronze or steel cylindrical shell G is fitted into the casting A, surrounds the piston D, and is held in place by the gland H and the screwed plug I. The shell G is furnished with internal grooves g and g' and external grooves g^2 and g^3 , connected by radial holes g^4 and g^5 , the purpose of which will be described later. The gland H is adjustably secured to casting A by studs h and nuts h' h^2 and is provided with a lubricating-recess h^3 .

A cover or hood K serves to protect the gland H and its adjusting-studs h and is secured to holder C by set-screws K.

In Fig. 1 is shown such portions of a screen as ordinarily constructed as is necessary to explain the working of the device. L is the screen-plate, provided with slots l and secured 5 by screws l' to the framework M, which is secured to the sides N of the screen-body.

Between the sides N and the framework O of the screen-body and secured to the four edges of the wooden diaphragm-plate P is the 10 rubber diaphragm Q. To the under side of diaphragm-plate P is the cast-iron plate R, secured to P by bolts r and to diaphragm-rod r' by set-screw r'.

To the under side of screen-body O is bolted 15 a cast-iron bridge-tree S, provided with a cap s, secured by bolts s' and holding in place a bronze bushing s'', serving as a guide for diaphragm-rod r', through which it passes.

Threaded on diaphragm-rod r' are the two 20 nuts r'' r'.

Encircling the diaphragm-rod r' and pressing against the nut r'' and the bridge-tree S is the helical spring T.

The device operates as follows: The diaphragm-rod r' being in its lowest position and 25 unscreened pulp in the space above screen-plate L, compressed air or the operating medium enters groove g³ through the hole a⁵, Fig. 4, and passing through radial holes g⁵, groove 30 g', groove d', and radial holes d⁴ enters the chamber d⁶ and acting on the piston D raises same until the top edge of groove d reaches the lower edge of groove g and the air is free to pass into the atmosphere through chambers d⁷ d⁸, radial holes d², grooves d g, radial holes g⁴, groove g², and radial holes a⁶. (Shown on Fig. 1 and Fig. 3.) This is the up- 35 stroke of the diaphragm, which clears the slots l in the screen-plate L of coarse particles of 40 pulp, as previously described. The lower edge of groove d having reached the top edge of groove g', as shown in Fig. 1, the supply of compressed air is cut off, so that the under side of piston D is subject to atmospheric 45 pressure only, and the pressure of the spring T, acting between the nut r'' and bridge-tree S, in addition to the weight of the diaphragm and its moving parts and the weight of the water and pulp above the diaphragm, returns 50 the piston D to its first position and completes the downstroke of the diaphragm, producing the vacuum-stroke, as already described, drawing the fine particles of pulp through the slot l in screen-plate L, which particles pass out 55 of the screen through openings. (Not shown on the drawings.)

The number of strokes of diaphragm is governed by the valve which admits air at a⁵.

While best results are obtained by allowing 60 the diaphragm to return by gravity, it can be returned by the air-pressure, if desired, by arranging the air-passages in piston D and shell G with that object in view.

The air-cushion formed when the piston D

is returning to its lowest position eliminates 65 the jar produced by the cam-shoes and cams as usually constructed.

The screwed plug I and the adjustable gland H provide means for adjusting the relative positions of grooves in piston D and shell G 70 to compensate for constructive inaccuracy in location of diaphragm-rod r' when screens are built.

It is intended to incorporate the essential parts of the above device in such castings and 75 holders as will enable it to be applied to existing screens.

Various slight changes might be resorted to in the relative arrangement of parts shown and described without departing from the 80 spirit and scope of my invention. Hence I would have it understood that I do not wish to confine myself to the exact construction of parts herein shown and described; but,

Having fully described my invention, what 85 I claim as new, and desire to secure by Letters Patent, is—

1. The combination of a screen-plate dia- 90 phragm, a fluid-pressure motor and means connecting said motor directly with the screen-plate diaphragm.

2. The combination with a screen-plate dia- 95 phragm; of a piston connected directly therewith, and fluid-pressure mechanism for controlling said piston to operate the diaphragm.

3. The combination with a screen-plate dia- 100 phragm, and a piston connected directly therewith, of a casing around said piston adapted to direct fluid beneath the piston to lift the diaphragm and a spring to assist the weight 100 of the parts, to lower the diaphragm.

4. The combination with a screen-plate dia- 105 phragm, of a piston connected directly therewith, a spring normally forcing said piston in one direction, and fluid-pressure mechanism 110 for controlling the movement of said piston in the other direction.

5. The combination with a screen-plate dia- 110 phragm, of a rod connected directly therewith, a spring on said rod normally pressing the 115 same downward, a piston on the lower end of said rod, a casing around said piston, and grooves and ducts in said casing and piston to admit a fluid below the piston to raise the same and permit the escape of said fluid when the piston reaches the desired height.

6. The combination with a screen-plate dia- 120 phragm, of a rod connected directly therewith, a spring on said rod pressing the same downward, a piston on the lower end of said rod, a casing around the piston, and inlet and outlet grooves and ducts in the piston and casing to direct the passage of a fluid to raise the piston and escape from beneath the same when the piston reaches a predetermined height, to 125 permit the spring and weight of parts to lower the piston, rod and diaphragm.

7. The combination with a screen-plate dia-

phragm, of a rod connected directly with said diaphragm and extending downward therefrom, a frame, a casing secured in the frame, a hollow piston in said casing, a removable plug in the frame below the piston closing the lower end of the casing, and said casing, frame, and piston having grooves and ducts therein to direct the passage of a fluid into and below the piston to elevate the same and permit the

escape of said fluid when the piston reaches a predetermined height.

In testimony whereof I have signed this specification in the presence of two subscribing witnesses.

GEORGE HENRY MARR.
